UNITED STATES PATENT OFFICE.

GEORGE CAMPBELL, OF TORONTO, ONTARIO, CANADA, ASSIGNOR OF ONE-HALF TO JOHN RICHIE, JR., OF SAME PLACE.

LAWN-MOWER.

SPECIFICATION forming part of Letters Patent No. 339,616, dated April 13, 1886.

Application filed March 25, 1884. Serial No. 125,509. (No model.) Patented in Canada July 7, 1884, No. 19,694.

To all whom it may concern:

Be it known that I, GEORGE CAMPBELL, a subject of the Queen of Great Britain, residing at Toronto, in the county of York and Province of Ontario, Canada, have invented a new and useful Improvement in Lawn-Mowers, of which the following is a specification.

My invention relates to certain improvements in mowing-machines for lawns or pleasure-grounds; and it consists in the novel construction and combination of parts hereinafter described and claimed, and illustrated in the accompanying drawings, in which—

Figure 1 is a plan of my machine. Fig. 2 is a section on the line *x y*, certain parts being broken away. Fig. 3 is a plan of the lever mechanism controlling the knives. Fig. 4 is a sectional elevation of the same. Figs. 5 and 6 are details of separate joints of the said levers.

20 A is the frame of the machine, of the shape shown, having extending arms B, to which the upper knife, C, is attached. The frame A has a slot, *a*, which serves as a bearing for the axles of the driving-wheels. These axles extend no farther through the slot than is sufficient to secure them by means of the jam-nuts *b* and *c*. The driving-wheels have inside gearing-teeth, E, which mesh with the tooth-wheel F. (Shown in dotted lines in both figures.) This wheel F is journaled on a shaft, G, borne in solid bearings in the frame A, on which is also journaled the tooth-wheel H, which meshes with the pinion I, which is journaled on the crank-shaft J, which has solid bearings in the frame A. In 35 the center of this shaft is the crank K, carrying the driving or connecting rod L, which terminates in the knuckle-joint M, which connects to the jointed levers before mentioned.

The top knife, C, which may also be considered as a knife-guard, is rigidly secured to the frame A, which it also helps to brace. Beneath it are two other knives of precisely the same construction. On the top knife, C, is the center pin, N, of this combination of levers firmly riveted. On this pin is pivoted a two-armed lever, O, extending each side of the pivot. One end of this lever is jointed to the lever P, which is pivoted on a pin, Q, securely riveted to the lower knife. The other end of lever O is jointed to the lever R, pivoted to the pin S, which is riveted to the center knife. For the

working of this pin a slot is cut in the upper knife, as, for the working of the pin Q, slots are cut in the two upper knives. Slots T are also cut in the whole of the knives through which bolts pass. This arrangement secures the parallel motion of all the knives. It will be seen that the joint at U carries the end M of the connecting-rod, which actuates these levers. When the crank K is set in motion, its 60 half-revolution straightens the toggle-levers and causes the knives to give two cuts, the top knife being stationary, the middle knife moving to the right making one cut, and the lower one to the left making a second. Another half-revolution causes the knives to reverse their movements, making two cuts, thus making four cuts to one revolution of the crank. The knife-teeth have square edges, instead of the usual beveled ones, and, being pressed together by the 65 bolts *t t*, passing through the slots T T, the constant friction sharpens the back teeth at the same ratio as the front ones wear and become dull, and when thought necessary the bolts *t t* can be removed. The lower knives may be 70 turned round, and with them the said conditions of sharpening, the dull edges being at the back and the others at the front ready for work.

V are dividers.

W is a guard extending the whole length 80 (and, preferably, consists of a curved or rounded metal plate secured to said lower knife by bolts or other suitable means,) of the lower knife, to protect it from entering the ground if the handle be lifted too high. This guard 85 reciprocates with the lower knife in its movement.

If it be desired, in case of obstruction, to drive the machine by other means than the wheels D for a short time, this object may be obtained 90 by the wheels D being thrown out of gear. By loosening the jam-nuts *b* and moving said wheels back they are released from meshing with the tooth-wheels F. The next step is to throw the bevel-wheel X into gear with the 95 wheel Y. This wheel Y is keyed on the shaft Z, which passes through the frame A, and is riveted to the universal joint *e*. By adjusting the set-screw *f* in the collar *g* the shaft Z is pushed down, and the wheel Y meshes with the 100 wheel X. On the universal joint *e* is a square socket holding loosely, and with room in it to

travel to and fro, the end of the crank-handle *h*, which is set in bearings *i*, extending upward from the wood handle *j*, so that when the wood handle *j* is elevated or depressed the push of 5 the crank-handle *h* on the universal joint *e* and shaft *Z* is not affected thereby. The crank-handle *h*, being turned by hand, thus actuates the wheel *H*, and consequently the crank *K*, and puts the knives in motion.

10 *k* is a follower adjustable by means of a set-screw, in the usual manner.

l is a metal hood extending the whole length of the knives and secured or hinged to the top knife. Its object is to prevent the grass or 15 débris from interfering with the jointed levers.

m is a shield of thin metal kept in position by being bolted to the frame *A* at *n*, and serves to protect the driving-wheel gear from injury by stones or other obstructions. It is shown 20 broken away in the drawings, in order to show the interior gear of the driving-wheel.

What I claim as my invention, and desire to secure by Letters Patent, is—

1. In a mowing-machine, the combination, 25 with the upper knife rigidly secured to the frame of the machine, and provided with back and front V-shaped teeth with square edges, of the two lower knives provided with similar back and front teeth moving in opposite directions and each connected with the operating-lever by bolts working in slots in the knives, 30 substantially as described.

2. In a mowing-machine, the combination, with the three knives constructed as shown, of a lever pivoted at its center to the fixed knife 35 and secured to the connecting-rod of the machine at one end, and short levers connecting at one end to the arms of the pivoted lever, and at their other ends connected to the center and lower knives, respectively, substantially 40 as described.

3. In a mowing-machine, the combination, with the knives constructed as shown, of the guard *W*, consisting of a curved or rounded plate extending the entire length of the lower 45 knife and secured to and reciprocating therewith, substantially as and for the purpose described.

4. In a mowing-machine, the combination of the crank *K*, connecting-rod *L*, toggle-levers 50 *O P R*, and the knives connecting with said toggle-levers, substantially as described.

5. The combination, with the knives, of the toggle-levers *O*, *P*, and *R*, and pins *S N Q*, the center pin, *N*, being riveted to the top knife, 55 the pin *S* to the second knife, a slot being made in the top knife for its passage, and the pin *Q*, riveted to the bottom knife, with similar slots in the top and middle knives, as and for the purpose specified.

G. CAMPBELL.
